PALM FROND FIGURE

Norwood R. Warehime, 704 W. 34th St.,
Baltimore, Md. 21211

Filed Oct. 20, 1970, Ser. No. 25,573

Term of patent 14 years

Int. Cl. D11—02

U.S. Cl. D29—23 E

The drawing is a front elevational view of a palm frond figure showing my new design, the eyes and nose being deeply recessed, the mouth being slightly recessed and the back being plain and having conventional curve of the palm frond.

I claim:

The ornamental design for a palm frond figure, as shown and described.
